Application April 2, 1948, Serial No. 18,546

6 Claims. (Cl. 121—157)

1

This invention relates to reciprocable fluid dispensing members and fluid-actuated motors therefor, e. g., showers for performing wetting, washing, cleaning, or analogous functions. More particularly, the invention relates to reciprocating devices of this character for use on paper machines or the like.

In the paper making art, it is essential for the satisfactory and efficient operation of the paper making process that various portions of the paper making machinery, such as the Fourdrinier wires, felts, cylinder moulds, screens, and extractor rolls, be maintained in a clean condition free of pulp, fibers, dirt, and other debris. Water showers are ordinarily provided at the desired locations to accomplish the necessary cleaning or washing. Water showers are also utilized for other purposes such as wetting of felts or foam breaking on stock tanks.

Such devices are preferably of the reciprocating type in which the shower tube and its nozzles are moved back and forth over the surface or structure to be showered. As a result of the reciprocating movement of the shower, streaking, non-uniform wetting, or unnecessary wearing of the felts, wires, screens, or other parts of the paper machine due to continued impingement of a liquid stream at one spot are avoided and, in addition, a substantial reduction in shower liquid requirements is realized. Reciprocation of the shower tube permits the use of fewer nozzles spaced farther apart and at the same time accomplishes an equivalent or even superior degree of cleaning at a higher nozzle pressure and with smaller nozzle orifices but with a substantially decreased volume of shower liquid as compared with the requirements of a non-reciprocating shower.

In the usual application of such showers in the paper making art, the wash fluid is water. However, in order to insure continuous operation of the showers and to avoid plugging of the nozzles, it is essential that a supply of adequately filtered water be available. Such pretreated water is also particularly well suited for use as a motive fluid in the operation of a hydraulic motor or other hydraulic actuator for reciprocating the shower head. Obviously, water which has been filtered and otherwise pretreated to render it suitable for use in the paper machine showers represents a material of substantially increased value, and precautions must be taken to minimize the loss of such water from the system and to reutilize both the shower water and the ex-

2

haust motive fluid in a manner as efficient and inexpensive as possible.

Accordingly, it is a primary object of the present invention to provide a novel and improved reciprocating fluid dispensing apparatus and more particularly a novel fluid-actuated motor for such apparatus.

A more specific object of the invention is to provide a reciprocating shower in which substantial economies are achieved in the consumption of valuable shower fluid and in the reutilization thereof.

A related object of the invention is to provide, in a hydraulically actuated reciprocating shower, flow control means of a type previously unavailable for independently regulating the fluid pressure at the nozzles and the rate of reciprocation of the shower head.

A further object of the invention is to provide a hydraulically actuated reciprocating shower in which exhaust motive fluid from the actuating device is combined with the fluid stream entering the shower head or tube.

An additional object of the invention is to provide, in a hydraulically actuated reciprocating shower, a hydraulic motor in which exhaust motive fluid is not discharged externally of the motor but instead is bled directly into the fluid stream being supplied to the shower head or nozzle unit.

Another object of the invention is to provide a reciprocating shower in which a fluid from a common supply source is directed in part to the shower head and in part as motive fluid to operate a hydraulic reciprocating device and in which exhaust motive fluid from the reciprocating device is combined with the fluid portion being supplied to the shower head.

A still further object of the invention is to provide, in a hydraulically actuated reciprocating shower having a common fluid supply for both the nozzles and the hydraulic actuator, separate control means for independently regulating fluid pressure at the nozzles and the rate of reciprocation of the shower head.

Another object of the invention is to provide, in a hydraulically actuated reciprocating shower, means for combining exhaust motive fluid from the hydraulic actuator with the fluid stream entering the shower head and also control means for independently regulating the flow of fluid to the shower head and to the hydraulic actuator.

Still another object of the invention is to provide a shower for paper machines or the like having a reciprocating tubular shower head

which may be rotatively adjusted by rotating the head about its axis to a desired position and which may be releasably locked in this position for operation of the shower.

Yet another object of the invention is to provide a reciprocating shower for paper machines and the like, in which means are provided at either or both ends of the extended shower tube for compensating for misalignment thereof due to sagging or bending.

Other objects and advantages of the invention will be apparent from the following detailed description of the invention and the accompanying drawings, in which:

Fig. 1 is an elevational view of a reciprocating shower embodying the novel features of my invention and illustrating the relative positions of the shower head and the hydraulic actuator;

Fig. 2 is a longitudinal sectional view on an enlarged scale of the shower head with the nozzles shown in elevation;

Fig. 3 is an enlarged fragmentary view of an axial section through one of the nozzles shown in Fig. 2;

Fig. 4 is a fragmentary sectional view on a reduced scale of the shower head showing a modified nozzle structure;

Fig. 5 is a longitudinal sectional view of the hydraulic motor shown in Fig. 1 taken along the line 5—5 of Fig. 6 and showing the motor piston approaching the righthand end of its stroke;

Fig. 6 is a longitudinal section view through the hydraulic motor, at 90° from the view shown in Fig. 5, taken principally along the line 6—6 of Figs. 5 and 13 but with the section through the right end or control portion of the motor being taken along the line 6—6 of Fig. 15;

Fig. 7 is a fragmentary longitudinal sectional view similar to Fig. 6 showing the motor piston at the extreme righthand position of its stroke;

Fig. 8 is a longitudinal sectional view similar to Figs. 6 and 7 but showing the motor piston at the extreme lefthand position of its stroke;

Fig. 9 is a longitudinal sectional view similar to Fig. 5 and taken along the line 9—9 of Fig. 8;

Figs. 10, 11, 12, 13, and 14 are transverse sectional views through the hydraulic motor taken along the lines 10—10, 11—11, 12—12, 13—13, and 14—14, respectively, in Fig. 6;

Fig. 15 is a right end view of the device as shown in Fig. 6;

Fig. 16 is a transverse sectional view taken along the line 16—16 of Fig. 2;

Fig. 17 is an elevational view on an enlarged scale of the hydraulic motor end of the device showing the details of the adjustable motor support;

Fig. 18 is a fragmentary view of the underside of the motor support taken along the line 18—18 of Fig. 17; and

Fig. 19 is a right end view of the device as shown in Fig. 17.

The reciprocating shower shown and described herein for purposes of illustrating my invention, but not by way of limitation, comprises generally an elongated shower head provided with nozzle outlets and operatively connected at one end to a reciprocating means comprising a hydraulic motor or actuator and supported at its opposite end for reciprocating movement. The hydraulic motor is provided with a fluid inlet and flow control means for controllably dividing the flow of fluid under pressure into separate streams, one of said streams being fed directly

to the shower tube and the other of said streams being diverted through the actuating mechanism of the motor. The effluent low pressure fluid, after passage through the actuating mechanism of the motor, is combined or commingled with the first named fluid stream and the combined streams flow into the shower tube or head.

Although my invention is particularly adapted for use in conjunction with paper machines for the various purposes described above, it will be evident that the invention is not limited to this specific application and that the several features of my invention may be utilized in numerous situations requiring a reciprocating or oscillating fluid dispenser, e. g., in lawn or garden showers for spraying devices.

Referring now to the drawings, one embodiment of the invention is shown by way of illustration and, as seen in Fig. 1, comprises a generally tubular shower head 20 which is slidably supported at its left end in a bearing assembly 21 for reciprocating horizontal movement therein and operatively connected at its right end to a reciprocator or hydraulic motor 22 for effecting horizontal reciprocating movement thereof. The hydraulic motor 22 consists of three main sections: the motor cylinder or hydraulic actuator section 23, the valve section 24, and the control section or fluid supply section 26, all of which are described hereinafter in greater detail. The valve section 24 and the control section 26 may be considered together as a fluid delivery section for the shower head 20 and the hydraulic actuator section 23.

As seen in Figs. 2 and 16, the shower head 20 comprises a reciprocably movable tube 27 having a plurality of button type nozzles 28 extending through the wall of the tube 27 at spaced points along its length. The tube 27 is coupled at its right end to a threaded pipe or conduit 29 by means of an internally threaded bushing 30 which is secured, as by brazing or welding indicated at 31, to the inner periphery of the tube 27 and engages the externally threaded end of the pipe 29. An externally threaded bushing 32 having a polygonal, and preferably square, central opening (Fig. 16) engages the internally threaded left end of the tube 27. An elongated guide and support member 33 having a corresponding polygonal external cross section extends centrally through the polygonal opening in the bushing 32 and is secured thereto, as by brazing or welding indicated at 34. The open end of the member 33 which extends through the bushing 32 into communication with the interior of the tube 27 is closed by means of a plug 36, secured by brazing or welding indicated at 37, in order to prevent fluid from escaping from the tube 27 other than by means of the nozzles 28.

Although the nozzles 28 may be disposed in any desired pattern or spaced locations in the tube 27, ordinarily, only a single row of nozzles is necessary in order to accomplish the desired function such as cleaning, washing, wetting, or foam breaking. Accordingly, it is an important feature of my invention that means are provided for rotatively adjusting and releasably locking the tube 27 in any desired rotary position, relative to the coaxial guide and support member 33 whereby the single row of nozzles may be pointed in the desired direction.

The shower of my invention is of relatively great length and relatively narrow width with respect to its overall dimensions in order to facil-

itate its mounting singly or in batteries at any desired location or locations on the paper making machinery. The external shape of the shower is also designed to permit the entire shower to be rotated about its axis and readily mounted at any desired axial orientation. However, it is not always possible to position the entire shower in the exact location or at the exact angle desired, and consequently it is highly advantageous if the angular or rotary position of the shower head can be adjusted relative to the motor and the bearing structure to accommodate the needs of a particular installation. For example, when a reciprocating shower of the type herein disclosed is utilized for cleaning a rotating cylinder mould of a paper making machine, the shower head is preferably mounted in close proximity to the rotating cylinder mould with the liquid streams or jets from the nozzles being directed against the cylindrical surface at an angle selected for optimum washing efficiency. In certain instances, however, dependent upon the construction of the particular paper making machine involved, it may not be possible to mount the shower head sufficiently close to the cylinder mould and with the nozzles pointing in the desired direction unless provision is made in the construction of the shower to permit rotative adjustment of the shower head with respect to its supporting structure over a relatively wide angular range. Moreover, it may be necessary to change the angular position of the shower head from time to time since the optimum angular orientation varies with many operating factors such as the speed of rotation of the cylinder mould.

As shown in Figs. 2 and 16, rotative adjustability of the tube 27 is achieved through a releasable locking means for coupling the left end of the tube 27 to the right end of the member 33. The left end of the tube 27 is provided with a plurality of circumferentially spaced grooves 38 (Fig. 16) which extend longitudinally and inwardly of the tube 27. A plurality of clamping dogs 39 extend radially from within the member 33 and through openings 41 provided in the flat sides thereof. In the specific form of the invention illustrated in the drawings (Figs. 2 and 16), the member 33 has a square external cross section and, accordingly, four dogs set at 90° spacings are provided. The outer ends 42 of the dogs 39 are bent inwardly in the direction of the tube 27 and are adapted to be received in the grooves or recesses 38. The inner ends of the dogs 39 have flattened portions or heads 43 of greater diameter than the openings 41 in order to prevent the dogs 39 from falling out of the member 33 when the apparatus is being dismantled or reassembled or during rotative adjustment of the tube 27.

A clamping collar 44 having a polygonal center opening 46 is slidably mounted on the member 33 and is adapted to be moved along the member 33 to permit an extended circumferential lip or rim portion 47 to overlie the bent ends 42 of the dogs 39 for retaining the same in clamped engagement with the grooves 38. A setscrew 48 extends through the collar 44 into an opening in one side of the member 33 in order to retain the collar 44 in clamping position when the dogs 39 are in locked engagement with the tube 27.

When the shower has been installed on a paper machine, the direction of the nozzles 28 may be regulated by releasing the setscrew 48, sliding the collar 44 outwardly on the member 33, disengaging the dogs 39 from the grooves 38 in the

end of the tube 27, and rotating the tube 27 at the threaded connections at each end thereof until the nozzles 28 are oriented in the desired direction. Having thus accomplished the desired rotative adjustment of the tube 27 relative to the member 33, the tube 27 may then be locked in this position by manually inserting the ends 42 of each of the dogs 39 into the nearest of the grooves 38 and then sliding the clamping collar 44 over the ends 42 and tightening the setscrew 48.

A removable flushout plug 49 is threadedly secured in the wall of the tube 27 adjacent one end thereof. On occasions when the shower is shut down, the plug 49 may be removed and the tube 27 flushed out with water supplied through the pipe 29, as hereinafter described, in order to free the tube 27 of any possible accumulation of foreign matter which may obstruct or plug the nozzles 28.

The free outer end of the member 33 is received in and supported by the bearing assembly 21 (Fig. 1) which comprises a pair of opposed roller bearings 51 disposed in a vertical plane to engage the upper and lower flat sides of the member 33 and a pair of opposed roller bearings 52 disposed in a horizontal plane to engage the member 33 laterally. The bearings 51 and 52 are mounted in a supporting structure or housing 53 having a pair of depending plate members or legs 54. The bearing assembly 21 is attached to a convenient portion of the paper machine, such as an upright frame portion 56, by means of a plurality of screw clamps 57 which extend through the legs 54 into clamping engagement with the frame portion 56. The position of the bearing assembly 21 may be changed upwardly or downwardly on the frame portion 56 by manipulation of the clamps 57 to obtain alignment of the outboard end of the shower head 20.

Each of the roller bearings 51 and 52 is journaled in an elongated slot 58 in the housing 53 and is adapted to be adjustably positioned therein transversely of its axis of rotation. An adjusting screw 59 extends into each slot 58 and is adjustable therein to provide at its inner end an adjustable stop for the roller bearing. Thus, transverse movement of each bearing is limited in one direction by the end of the slot 58 and in the other direction by the inner end of the screw 59.

The transverse adjustability of the roller bearings is particularly important in the case of the upper and lower bearings 51 which guide and support the member 33 in a vertical plane. Dependent largely upon the overall length and weight of the shower head 20, a certain degree of sagging or bending of the tube 27 tends to take place, inasmuch as it is supported only at its ends, causing the member 33 to occupy a misaligned and somewhat slanted position sloping downwardly and inwardly from its outer end toward the tube 27. It will be seen that the load is borne by the lower bearing 51 resting at all times on its screw 59 and that the required relative position of the upper bearing 51 will be determined by the extent of sagging and misalignment of the tube 27. Thus, if the bearings 51 are to perform their function of supporting and guiding the travel of the member 33, they cannot be disposed in fixed positions without creating, under practical operating conditions, excessive resistance against the operation of the hydraulic motor even to the point of stalling said motor or fracturing or bending the shower head. There-

fore; the adjustable screws 59 are provided to permit the bearings 51 to be positioned in their proper relation to accommodate misalignment of the member 33 while remaining at all times in rolling contact with the upper and lower sides thereof.

In an analogous manner the lateral roller bearings 52 may be adjusted to compensate for possible irregularities or deviations from straight line movement of the member 33 in the bearing assembly 21 in a horizontal plane.

It will be evident that possible sagging or bending of the tube 27 will also tend to cause misalignment of the pipe 29 at the inboard end of the shower head and consequent resistance to the normal operation of the hydraulic actuator section 23. As described below in detail, this condition is compensated for by means of an adjustable mounting platform or base 60 (Fig. 1) for the motor 22, said base being movable in a vertical plane about its pivoted outer end as will herein-after appear.

As shown in Fig. 3, the button type nozzle 28 may comprise a head portion 61 and a threaded stem portion 62 engaging a complementary threaded opening in the wall of the tube 27. The head portion 61 is in sealed engagement with the tube 27 by means of a locking gasket 63 and a locking washer 64 disposed thereover. Extending through the stem portion 62 is an orifice or channel 66 the diameter of which is greatly exaggerated in Fig. 3 for the sake of clarity. The head portion 61 is provided with a hexagonal recess or socket 67 communicating with the channel 66 and serving as an outlet for a fluid stream flowing through the channel 66 from within the tube 27. The socket 67 also is adapted to receive the head of a socket wrench or key employed for inserting and removing the nozzles 28 from the tube 27.

Although the diameter of the orifice or channel 66 in the nozzle 28 may vary within relatively wide practical limits, it is usually preferred to employ relatively small orifice diameters, for example, of the order of .001 to 0.1 inch, in order to realize the full cleaning, wetting, or washing power of a relatively high pressure directed liquid stream. In general, a number of factors must be taken into consideration in determining orifice diameter, among which may be mentioned the quantity of water needed to perform effectively the desired function of the shower, the proximity and direction of the nozzles with respect to the surface or structure being wetted or cleaned, and the pressure of the shower fluid used. In addition, on a given paper making machine any one of the aforementioned factors may vary (the others being constant) with such variables as the nature of the shower fluid, operating speed of the paper machine, type and thickness of paper produced, consistency of stock, atmospheric temperature and humidity, etc.

In order to utilize nozzles having relatively small orifice diameters, it is important to have available an ample supply of properly filtered water or other shower liquid which is substantially free of all particles of foreign matter which might obstruct or plug the orifices. Accordingly, it will be seen, as hereinbefore mentioned, that a suitable water pretreatment system is an important adjunct to the satisfactory operation of a shower employing small diameter orifice nozzles. In general, the required degree of clarity of water or other shower liquid for practical operation varies inversely with the cross-sectional area of the nozzle orifice.

In Fig. 4 there is illustrated an alternative nozzle structure 68 which may be more desirable for use in certain situations, particularly where an adequate water pretreatment system is not available and it is necessary to remove the nozzles frequently for cleaning purposes. In this modification, the nozzle 68 is not threadedly engaged with the wall of the tube 27 but instead is provided with an annular shoulder portion 69 which engages in abutting relationship with a complementary shoulder portion or seat 71 in the wall of the tube 27. A sealing gasket 72 is disposed between the shoulder portion 69 and the seat 71. The nozzle 68 is retained in place in the tube 27 by means of a detachable strap or band 73 which encircles the tube 27 in overlying relationship with the nozzle and which is provided with an opening 74 of larger size than the outlet of an orifice or channel 76 in the nozzle and is adapted to register therewith. The retaining band or guard 73 is releasably held in nozzle-retaining position by means of a suitable locking device such as a buckle or other fastener 77. Detents or slotted portions 78 are provided in the head of the nozzle to permit a puller tool to be inserted therein for lifting the nozzle out of its seat.

It will be seen that the combination of an easily removable nozzle seated in the wall of the shower tube and a detachable guard or retaining means cooperating therewith will in certain cases be more convenient and desirable than the threaded type of nozzle illustrated in Fig. 3.

Referring now to Figs. 5 to 15, the structural details and operation of the hydraulic motor 22 will be described.

The pipe 29, which is coupled at its left end to the tube 27 (Fig. 1), extends longitudinally through a cylinder head 81 (Fig. 6) in the left end of the hydraulic actuator section 23 into a working cylinder 82 and thence through a second cylinder head 83 at the right end of section 23 into a fluid delivery or mixing chamber 84 in the valve section 24, hereinafter described in greater detail. Suitable packing glands 86 and 87 are provided in the cylinder heads 81 and 83, respectively.

A double-acting piston 88 is carried on the pipe 29 which thus functions both as a piston rod for the hydraulic actuator section 23 and as a fluid supply conduit for the shower head 20 in a manner to be described presently. A cored fluid passageway or channel 89 in the hydraulic actuator section 23 forms a continuation of a cored channel 90 (Fig. 5) in the upper portion of the valve section 24 and communicates by means of a U-shaped bend 91 with the cylinder 82 serving both as a motive fluid inlet and exhaust for the left side of the piston 88 as will hereinafter appear. Another fluid passageway or cavity 92 in the cylinder head 83 and having an arc-shaped transverse cross section (Fig. 11) communicates with the cylinder 82 on the right side of the piston 88 for supplying and discharging motive fluid, as hereinafter described. The cavity 92 is connected by means of a vertical duct 93 with a longitudinal cored passageway 94 (Fig. 5) in the upper portion of the valve section 24.

The pipe 29 terminates in an open end 95 (Fig. 6) within the chamber 84 and is threaded along a portion of its inner end. A pair of annular collars 96 and 97, the latter being of slightly larger diameter, are threadedly secured to the pipe 29 and are adapted to be positioned in any desired abutting or spaced relation along

the threaded portion of the pipe. A pair of endwise slots 93 are formed in opposite sides of the pipe wall and by undersizing the internal threads of the collars 96 and 97 a resilient locking effect is obtained when the collars are screwed on the pipe 29 causing the slotted halves of the pipe to be drawn toward each other and thereby retaining the collars firmly in place. Obviously, other suitable means, such as set screws, may also be utilized for retaining the collars 96 and 97 against inadvertent movement thereof.

The upper portion of the valve section 24 above the fluid delivery chamber 84 also contains a double-acting, fluid-actuated, piston-type master valve or main valve 99 which is reciprocably slidable in a main valve cylinder 101. Reciprocating movement of the valve 99 is controlled by the flow of motive fluid, as hereinafter described, through a cylindrical pilot valve 102 which is mechanically reciprocable in a pilot valve cylinder 103 having a common wall with the cylinder 101 disposed thereover. The flow of motive fluid between the cylinders 101 and 103 is accomplished by means of complementary ports, hereinafter referred to specifically, in the common cylinder wall and in the pilot valve 102 which are brought into registry by sliding movement of the latter.

Secured to opposite ends of the pilot valve 102 by means of screws 104 are depending abutments or shift fingers 106 which extend through slotted portions 107 in the bottom wall of the cylinder 103 into the path of travel of the collars 96 and 97. Longitudinal reciprocating movement of the pipe 29 causes the collars 96 and 97 to engage the shift fingers 106 alternately thereby reciprocating the pilot valve 102 in its cylinder 103 and reversing the flow of motive fluid to the main valve 99 and the piston 88 in the cyclic manner described below. Although the collars 96 and 97 are shown in abutting relation in the drawings, it will be evident that the length of the stroke of the pipe 29 may be regulated by adjusting the distance between the collars. By detaching the control section 26, access to the chamber 84 is readily obtained for adjusting the setting of the collars 96 and 97. It will be noted that the collar 97 which is remote from the control section 26 is of slightly larger diameter than the collar 96 to facilitate its adjustment by means of a suitable tool.

The control section 26 of the motor 22 comprises a fluid inlet chamber 108 (Fig. 6) having a fluid feed passageway 109 adapted to be connected to a suitable liquid supply source such as clear filtered water. Manually operable flow control-valves 111 and 112 extend into the chamber 108 and cooperate with valve seats 113 and 114, respectively, to proportion the flow of fluid through a pair of inlet ports 115 and 116, respectively. The fluid stream passing through port 115 from chamber 108 enters a cored passageway 117 (Fig. 5) in the valve section 24 and is ultimately supplied as motive fluid for the hydraulic actuator section 23. The fluid stream passing through the port 116 flows directly into the chamber 84 and supplies the shower head 20 through the hollow piston rod or pipe 29. A pressure gage 118 is connected to a pressure tap or duct 119 (Fig. 14) which communicates through a horizontal cavity 121 (Fig. 5) and a vertical duct 122 (Fig. 13) with the fluid delivery chamber 84 to indicate the fluid pressure therein which

is the pressure of the fluid being supplied through the pipe 29 to the shower head 20.

In the operation of the shower, high pressure water from the supply source enters the chamber 108 through the feed passageway 109 (Fig. 6). By manipulation of the flow control valves 111 and 112, the flow of water is divided into two parallel streams one of which flows through the port 116 into the chamber 84 as the major part of the fluid supply for the shower head 20 and the other of which flows through the port 115 into the passageway 117 (Fig. 5) for ultimately actuating the motor. The water in the fluid delivery or mixing chamber 84 passes through the open end 95 of the pipe 29 and flows therethrough into the tube 21 from which it is directed outwardly through the nozzles 23.

In Figs. 5 and 6, the piston 88 is shown moving toward the right end of the cylinder 82 with the collar 96 on the end of the piston rod 29 coming into contact with the righthand shift finger 106 and ready to shift the pilot valve 102 to the right end of its cylinder 103. In this position, high pressure water entering the passageway 117 from the inlet port 115 flows into the free space around a reduced portion 123 (Fig. 5) in the valve 99. A portion of the water flows from this space downwardly, through a port 124 (Fig. 6) in the common cylinder wall and another port 126 in registry therewith in the pilot valve 102, into the interior of the pilot valve 102. The high pressure water within the pilot valve 102 exerts pressure, through a port 127 and a port 128 in registry therewith in the common cylinder wall, on the left end of the valve 99 retaining it at the right end of its cylinder 101. Water which was previously in the right end of the cylinder 101 has been displaced therefrom by movement of the valve 99 to the right, the water exhausting through a port 129 (Fig. 6) in the common cylinder wall and thence downwardly through the free right end of the cylinder 103 and its righthand slotted opening 107 into the fluid delivery chamber 84. The water thus exhausted into the mixing chamber 84 from the right end of the cylinder 101 is combined or commingled with the portion of fluid flowing into the tube 29 from the chamber 84.

With the master valve 99 thus retained in its extreme righthand position, high pressure water from the passageway 117 (Fig. 5) flows through the reduced portion 123 of the valve 99 and thence into the cored passageway 90 as indicated by the arrows in Fig. 5. From the passageway 90 the water flows through the passageway 89 and the bend 91 into the left end of the cylinder 82 (Fig. 6) thereby forcing the piston 88 toward the right. The water on the right side of the piston 88 exhausts through the arc-shaped cavity 92 and its communicating vertical passageway 93 into the cored passageway 94 (Fig. 5). From passageway 94 the exhaust water flows through an opening 131 in the side wall of the cylinder 101 into the free space around another reduced portion 132 in the valve 99 and thence downwardly through an opening 133 in the common cylinder wall, around the outside of the cylindrical pilot valve 102, and through a port 134 in the bottom of the cylinder 103 into the fluid delivery or mixing chamber 84. The exhaust motive fluid from the hydraulic actuator section 23 thus entering the chamber 84 is combined and commingled with the shower fluid being supplied thereto through the inlet port 116.

Referring now to Fig. 7, the piston 88 is illus-

trated at the extreme righthand position of its stroke arrived at a short time after the position shown in Figs. 5 and 6. The piston rod 29 has also reached the right end of its stroke, and the pilot valve 102 has likewise been shifted to the right by engagement of the collar 96 with the righthand shift finger 106. A port 135 in the pilot valve 102 is now in registry with the port 124, and the port 129 is now aligned with an end port 136 in the valve 102. As a result of this shifting of the pilot valve 102, high pressure water is connected to the right end of the master valve 99 by flowing from passageway 117 (Fig. 5) into the free space around the reduced portion 123, downwardly through the registered ports 124 and 135, longitudinally through the interior of the pilot valve 102, and upwardly through the registered ports 136 and 129 into the right end of the cylinder 101, as indicated by the arrows in Fig. 7.

As the master valve 99 begins to move toward the left, water is displaced from the left end of the cylinder 101 and exhausts downwardly through the port 128, through the free left end of the cylinder 103 and its slotted lefthand opening 107, and into the mixing chamber 84 to be combined with the water flowing therefrom to the shower head 20.

When the valve 99 has reached the extreme left end of its cylinder 101, as shown in Figs. 8 and 9, a reversal of the water feed and exhaust connections to the cylinder 82 has occurred. High pressure water now flows from the passageway 117 (Fig. 9) across the reduced portion 132, through the opening 131 into the passageway 94, downwardly through the duct 93 and the arc-shaped cavity 92, and into the right end of the cylinder 82 forcing the piston 88 to the left end of its stroke, as shown in Fig. 8. Exhaust water moving to the left ahead of the piston 88 flows through the bend 91, through the passageways 89 and 90, into the reduced portion 123 (Fig. 9), thence downwardly through a port 137 in the common cylinder wall, around the cylindrical pilot valve 102, through a port 138 in the bottom of the cylinder 103, and into the fluid delivery or mixing chamber 84. The exhaust motive fluid is again combined therein with the shower fluid being supplied through the inlet port 116.

When the piston 88 reaches the extreme left hand position of its stroke (Fig. 8), the pilot valve 102 is shifted to the left end of its cylinder 103 by engagement of the collar 97 with the lefthand shift finger 106 thereby reversing the flow of high pressure water to the master valve 99 which then moves to the right end of its cylinder 101 and completes the cycle.

As previously mentioned, possible sagging or bending of the tube 27 will tend to cause misalignment or cocking of the piston rod 29 coupled to the inboard end of the shower head. Obviously such a condition will result in a serious strain on the piston rod 29 and undesirable resistance against the normal aligned reciprocating movement of the piston 88 in its cylinder 82. To compensate for such adverse effects I have provided an adjustable mounting platform or base 60 which is shown in detail in Figs. 17-19.

A flat supporting plate 139 is disposed beneath the hydraulic actuator section 23 of the motor 22. A pair of opposed angle irons 141 are disposed longitudinally beneath the plate 139 and are secured by means of a plurality of screws 142 extending through the plate 139 into the cylinder heads 81 and 83. The angle irons 141 are con-

nected for pivotal movement, with a pair of upright angle irons 142 by means of a pair of bolts 143 and nuts 144, the upright angle irons 142 being fastened to a suitable portion of the paper machine such as the upright frame member 146. Extending between the outermost ends of the angle irons 141 and 142 and forming a triangular structure therewith is an adjustable connecting member comprising a pair of elongated rods 147 and 148 pivotally secured to a pair of tubular pivot members 149 and 151, disposed between the opposed sides of the angle irons 141 and 142, respectively. The rods 147 and 148 are threaded at their opposed end portions and are adjustably connected by means of an internally threaded sleeve or coupling 152 of hexagonal cross-section. By obvious manipulation of the coupling 152, the base 139 and the motor 22 may be raised or lowered about the pivot points formed by the bolts 143 to align the hydraulic actuator section 23 with the piston rod 29 and thereby compensate for cocking or slanting of the latter due to sagging or bending of the shower tube 27. In this manner I am able to eliminate binding and abnormal resistance to the proper operation of the piston 88.

From the foregoing description of the operation of the hydraulic motor 22, it will be seen that in my invention all of the valuable filtered water is ultimately supplied to the shower head 20. Exhaust motive fluid from the master valve cylinder 101 and from the hydraulic actuator cylinder 82 is not discharged externally of the motor but instead is returned directly, by means of cored passageways and valve ports within the motor, to the fluid delivery or mixing chamber 84 which supplies water to the shower head 20. Thus, the shower fluid being supplied to the unit is temporarily divided to provide a portion for operating the motor with such portion being returned to the main body of fluid at a more advanced point in its passage to the shower head.

Not only does my feature of internal recirculation of exhaust motive fluid have the obvious advantages of compactness and simplicity of operation, but there is also a considerable saving of power requirements and extra equipment costs which would be inherent in an external recirculation system wherein exhaust motive fluid from the cylinders 82 and 101 would be discharged exteriorly of the motor 22 to a supply tank and then repumped to the inlet chamber 108. Moreover, my invention eliminates wasteful recycling of the valuable clear filtered water through the reciprocating mechanism of the hydraulic motor which would be the case in an external system of recirculation wherein exhaust motive fluid is combined exteriorly of the motor with the total fluid stream being supplied to the system. In my invention, all of the exhaust motive fluid is combined with only the separate fluid stream entering the supply pipe 29 for the shower head 20.

Another important feature of my invention is the provision of independent flow control valves 111 and 112 in the fluid inlet chamber 108 whereby the flow of the parallel fluid streams to the shower head and to the motive mechanism may be separately regulated. This is an important advantage since it permits independent control over relatively wide ranges, dependent upon the fluid pressure available and upon the pressure drop through the motor, or the pressure at the nozzles 28 and the rate of reciprocation of the shower head 20. In the showers previously available, no provision has been made for such

independent regulation of these two operating variables when a common source of fluid supply was utilized for both the shower fluid and the motive fluid.

From an operating view point it is a considerable advantage affording a high degree of flexibility of performance to be able to adjust the fluid pressure at the nozzles without materially affecting the rate of reciprocation of the shower head, and vice versa. The valve 111 diverts a portion of the shower fluid through the hydraulic actuator section whereas the valve 112 functions in the nature of a pressure reducing valve to maintain the pressure of the main shower stream entering the chamber 84 below the pressure of the exhaust motive fluid being supplied thereto.

With the construction herein described, the rate of reciprocation or motor speed and the shower stream pressure can be regulated by mutual manual adjustment of the valves 111 and 112 to give any desired combination of the two operating variables. For example, if maximum motor speed is desired, valve 112 is completely closed and valve 111 is completely open thereby permitting the entire fluid supply to flow through the hydraulic actuator section 23 and thence into the chamber 84, the pipe 29, and the shower head 20. The shower may be shut down by completely closing both valves 111 and 112 to give zero motor speed and zero shower flow. High shower stream pressure with a low or moderate rate of reciprocation may be obtained by suitable manipulation of the valves 111 and 112.

Although the invention has been described primarily in connection with a single specific embodiment as illustrated in the drawings, it is to be understood that various modifications and equivalent constructions are contemplated within the scope of the invention as defined in the appended claims.

I claim:

1. A fluid-operated motor for effecting reciprocation of a fluid dispensing member comprising an elongated casing having a hydraulic actuator section at one end thereof, a fluid supply section at the opposite end thereof, and a reciprocable valve section intermediate said hydraulic actuator and fluid supply sections, a hollow piston rod extending into said casing through said hydraulic actuator section and terminating at an open end in said reciprocable valve section, a piston carried on said piston rod within said hydraulic actuator section for reciprocating movement therein, said piston rod being adapted to be coupled at its outer end to said fluid dispensing member, reversible valve structure disposed within said reciprocable valve section in flow communication with said hydraulic actuator and fluid supply sections for controlling the flow of a motive fluid alternately to and from opposite sides of said piston in said hydraulic actuator section, means for conducting fluid independently from said fluid supply section to said valve structure and to the open inner end of said piston rod, and means for commingling exhaust motive fluid from said valve structure with the fluid supplied to said piston rod.

2. A fluid-operated motor for effecting reciprocation of a fluid dispensing member comprising an elongated casing having a hydraulic actuator section at one end thereof, a fluid supply section at the opposite end thereof, and a reciprocable valve section intermediate said hydraulic actuator and fluid supply sections, a hollow piston rod extending into said casing through said hy-

draulic actuator section and terminating at an open end in said reciprocable valve section, a piston carried on said piston rod within said hydraulic actuator section for reciprocating movement therein, said piston rod being adapted to be coupled at its outer end to said fluid dispensing member, an elongated reciprocable main valve disposed within said reciprocable valve section in parallel relation with said piston rod for controlling the flow of a motive fluid alternately to and from opposite sides of said piston, an elongated reciprocable pilot valve disposed within said reciprocable valve section in parallel relation with said main valve, said pilot valve being actuated in response to reciprocating movement of said piston rod whereby to control the flow of motive fluid through said main valve, means for conducting fluid independently from said fluid supply section to said main valve and to the open inner end of said piston rod, and means for commingling exhaust motive fluid from said main valve with the fluid supplied to said piston rod.

3. A fluid-operated motor for effecting reciprocation of a fluid dispensing member comprising an elongated casing having a hydraulic actuator section at one end thereof, a reciprocable valve section adjacent said hydraulic actuator section for controlling the flow of a motive fluid to and from the latter, and a detachable valve chamber adjacent said reciprocable valve section at the opposite end of said casing, a hollow piston rod extending into said one end of said casing and terminating at an open end in said valve section, said piston rod being adapted to be coupled at its outer end to said fluid dispensing member, means for supplying fluid independently from said valve chamber to said reciprocable valve section and to the open inner end of said piston rod, and flow regulating valves in said valve chamber for independently controlling the flow of fluid to said reciprocable valve section and to said piston rod, said valve chamber being removable from the device whereby to provide ready access to said reciprocable valve section.

4. A fluid-operated motor for effecting reciprocation of a fluid dispensing member comprising an elongated casing having a hydraulic actuator section at one end thereof, a reciprocable valve section adjacent said hydraulic actuator section, and a valve chamber adjacent said reciprocable valve section at the opposite end of said casing, an elongated hollow piston rod extending into said one end of said casing through said hydraulic actuator section and terminating at an open end in said reciprocable valve section, said piston rod being adapted to be coupled at its outer end to said fluid dispensing member, reversible valve structure including a reciprocable pilot valve in said reciprocable valve section for controlling the flow of a motive fluid to and from said hydraulic actuator section, actuating means carried by said piston rod in adjustable relation thereon for effecting shifting movement of said pilot valve in response to reciprocation of said piston rod, and flow regulating valve means in said valve chamber for independently controlling the flow of separate fluid streams to said valve structure and to the open inner end of said piston rod, said valve chamber being detachable from said reciprocable valve section whereby to permit adjustment of said actuating means on said piston rod for varying the stroke of said piston rod.

5. A fluid-operated motor for effecting reciprocation of a fluid dispensing member comprising an elongated casing adapted to have said fluid

dispensing member extend longitudinally from one end thereof, said casing having relatively narrow transverse dimensions as compared with its longitudinal dimension whereby to facilitate mounting of a plurality of the motors in close side-by-side relationship, a hydraulic actuator section at said one end of the casing, a fluid supply section at the opposite end of said casing, a reciprocable valve section intermediate said hydraulic actuator and fluid supply sections, said sections being connected in end-to-end relationship for flow communication therebetween, a hollow piston rod extending into said casing at said one end thereof through said hydraulic actuator section and terminating at an open end in said reciprocable valve section, means including cored fluid passageways extending through said casing for supplying a motive fluid independently from said supply section to the open inner end of said hollow piston rod and through said reciprocable valve section to said hydraulic actuator section, and means for commingling exhaust fluid from said hydraulic actuator section with fluid supplied to said hollow piston rod.

6. A fluid-operated motor for effecting reciprocation of a fluid dispensing member, said motor comprising an elongated casing having a hydraulic actuator section at one end thereof adapted to be operatively connected to said fluid dispensing member, a fluid supply section at the opposite end of said casing, a reciprocable valve section intermediate said hydraulic actuator and

fluid supply sections, said sections being connected in end-to-end relationship for flow communication therebetween, means for conducting fluid from said fluid supply section through said reciprocable valve section to said hydraulic actuator section and also adapted to supply fluid independently to said fluid dispensing member, and means for commingling exhaust fluid from said hydraulic actuator section with the fluid supplied to said dispensing member.
